(57) **CLAIM**

The ornamental design for a lid for a painting container, as shown and described.

DESCRIPTION

FIG. 1 shows a perspective view of a lid for a painting container.

FIG. 2 shows a top view of the lid in FIG. 1.

FIG. 3 shows a bottom view of the lid in FIG. 1.

FIG. 4 shows a front view of the lid in FIG. 1.

FIG. 5 shows a rear view of the lid in FIG. 1.

FIG. 6 shows a left-side view of the lid in FIG. 1.

FIG. 7 shows a right-side view of the lid in FIG. 1; and, FIG. 8 shows another perspective view of the lid in FIG. 1 in a different configuration.

The portions of the design shown in broken or dotted lines are for illustrative purposes only and form no part of the claimed design.

1 Claim, 8 Drawing Sheets
